SHIELD FOR FOOD SERVICE CARTS OR THE LIKE

Victor D. Molitor, Englewood, Colo.

Application May 6, 1957, Serial No. 46,024

Term of patent 14 years

(Cl. D14—3)

FIG. 1.

FIG. 2.

FIG. 3.

Fig. 1 is a front perspective view of the shield for food service carts or the like embodying my new design;

Fig. 2 is a rear perspective view; and

Fig. 3 is an end elevation, on an enlarged scale.

The shield is transparent and the essential features of my design are shown in full lines.

I claim:

The ornamental design for a shield for food service carts or the like, as shown and described.
